UNITED STATES PATENT OFFICE.

ALDEN L. PUTNAM, OF NYACK, NEW YORK.

CONVEYER FOR SOLID MATERIALS.

SPECIFICATION forming part of Letters Patent No. 779,813, dated January 3, 1905.

Application filed August 16, 1904. Serial No. 220,899.

To all whom it may concern:

Be it known that I, ALDEN L. PUTNAM, a citizen of the United States, and a resident of Nyack, in the county of Rockland and State 5 of New York, have invented a new and Improved Conveyer for Solid Materials, of which the following is a full, clear, and exact description.

My invention relates to means for conveying solid materials.

The object of the invention is to provide for forcing such material as coal, grain, bricks, and small blocks of material of a general character through a pipe or duct to some predetermined spot. It is to be used to do the work for which chain-and-bucket or belt conveyers are now employed.

The conveyers now in use are objectionable in many respects. They require a return-line 20 of empty buckets or a belt, thus necessitating the construction of a double length of conveyer. They are as a usual thing restricted to work in a single plane. They cannot readily be adjusted at a plurality of points. 25 They usually require a filler, and they are expensive to install and require constant attention and many repairs to maintain them in working order. It is the object of my invention to provide a device which will accomplish 30 the same work and will be devoid of the objections mentioned above.

The invention comprises one or more movable receptacles adapted to convey material to a discharge-duct and force it into the duct 35 successively from the receptacles.

Reference is to be had to the accompanying drawings, forming a part of this specification, in which similar characters of reference indicate corresponding parts in all the figures. 40 Figure 1 is a front elevation showing a preferred embodiment of my invention, parts thereof being in section. Fig. 2 is a central vertical section of the same. Fig. 3 is a horizontal sectional view on the line 3-3 of Fig. 2, 45 parts being broken away to show elements located below that plane; and Fig. 4 is a sectional view on the line 4-4 of Fig. 1.

A represents the various portions of the frame of the machine, upon which is supported a hopper *a*, which is designed to be located

below the source of supply of material and to be fed therefrom by gravity. A series of receptacles *b* are designed to pass successively under the hopper and to receive material therefrom. In each of the receptacles is a 55 plunger *c*, which moves around with the receptacle to which it belongs and is designed to discharge the material therefrom when the receptacle comes under a pipe or duct *d*, which is designed for discharging the material from 60 the apparatus. It will be understood that the duct *d* may be of any desired shape and character and that it may extend in any direction and may be provided with curves and bends, also with branches, so that it can deliver material in any desired manner. It can also be made of flexible material, so as to deliver material first to one place and then to another.

For convenience the receptacles *b* are shown in the form of perforations through a rotatable disk or table *b'*. These perforations are preferably open at both ends, the top end being closed during most of the operation by means of a plate *d'*, mounted upon the frame *A* and carrying the hopper *a* and lower end 75 of the duct *d*. The disk or table is designed to rotate about a central shaft *e*. Upon the lower ends of the plungers are provided bearing devices, preferably in the form of rollers *c'*, which travel upon the track *f*. This track is 80 provided with an inclined portion *f'*, and a guard *f''* is located near the side thereof to engage with the rollers *c'* and keep them upon the track when the inclined portion is in operation.

It will be understood that the rotation of the table *b'* is in the direction of the arrow shown in Fig. 1 and that the track *f* is provided with an opening *f''*, in which the upper end of a piston *g*, provided with a horizontal projection *g'*, is adapted to rest. The upper end of this piston will normally be in the same plane as the upper surface of the track, so that the rollers *c'* can roll onto the piston in an obvious manner. Mechanism is provided so 90 timed that when a roller *c'* assumes this position the piston will be elevated, carrying with it the plunger *c* which happens to be above it and forcing the material from its receptacle *b* into the duct *d*. The further rotation of 95 100

the table will cause this receptacle and plunger to be carried along under the plate a' , cutting off the material in the duct d and preventing its falling back, and the roller c' will 5 continue to remain in an elevated position (on account of the horizontal projection g' upon the piston g) a sufficient length of time to prevent the lowering of the plunger until it has entirely passed the opening in the lower end 10 of the duct. When this point is reached, however, the roller c' will roll down the incline f' , guided when necessary by the guide f'' , and the piston g is so timed as to immediately descend in position ready for the next 15 roller c' . It will be understood that the receptacles or perforations are filled by gravity as they come under the hopper and that the rotation of the table cuts off the material between the hopper and the receptacles.

20 It will be obvious that the parts so far described may be modified through a wide range without departing from the spirit of the invention, and it will also be apparent that the means for operating the parts in the manner 25 described may take many forms. One of these forms is illustrated in the drawings and will be described, commencing with the power-shaft h . Upon this shaft is a pulley h' , driving a belt i , which operates a pulley j 30 upon a shaft k , which is journaled in the frame of the machine. The shaft k is provided with two worms l and l' . The worm l is designed to operate a worm-gear m upon a shaft n , and upon this shaft is mounted a 35 worm o , which has the usual grooves o' through one half of its circumference; but for the other half of its circumference the grooves are made straight and extend in planes perpendicular to the axis of the shaft e . This 40 portion of the grooves is indicated at o'' . A cog-wheel p is mounted upon the shaft e , upon which the disk b' rotates, as stated above. This cog-wheel is provided with a series of teeth p' , which are preferably conical in shape 45 and mesh with the grooves o' and o'' in a manner well understood. It will be obvious that the rotation of the shaft n will cause the tooth or teeth p' which happen to be in engagement with the grooves o' to travel in the direction of the arrow shown in Fig. 3 until the 50 portions o'' of the grooves come into engagement with the teeth, and during that portion of the rotation of the shaft n the teeth will remain stationary. The effect of this will be 55 obvious. The wheel p and disk b' being rigidly connected together by the shaft e , the disk will be caused to have an intermittent rotation, the pauses in the rotation occurring when the straight portions o'' of the grooves 60 o' are in engagement with the teeth p' . Engaging with the other worm, l' , upon the shaft k is a worm-wheel q upon a shaft g' , which carries a cam r . The cam r is designed to operate upon a roller s , secured to the lower 65 part of the piston g , which is guided in a

housing t on the frame A . The worm-wheel o and cam r are so timed by means of the intermediate operating devices and the setting of these two elements upon their shafts that during the pause in the rotation of the disk 75 b' , which comes when a wheel c' is directly over the piston g , the latter will be forced upwardly to the extent of its stroke.

The operation of this embodiment of the invention will be obvious. The device is 75 driven from the shaft h and more immediately by the shaft k . The disk b' is rotated one step by the wheel o , so that after a receptacle b is filled with material from the hopper a it will be caused to pass through a certain 80 portion of a revolution, and then the wheel will stop. Another receptacle, which has been filled and precedes the one referred to, will at this period be directly above the piston g , and the latter will immediately commence 85 to rise and force the corresponding plunger c upwardly in the receptacle or perforation b , so as to discharge the material into the duct d . The worm portions of the grooves o' will then come into action and cause the disk to 90 be rotated another step, which will carry the wheel c' out upon the projection g' and onto the inclined surface f' . As soon as the wheel c' leaves the surface g' the cam r will reach that portion of its stroke which will permit 95 the piston to descend, and the latter will drop to its original position ready to receive the next roller c' . The rotation of the disk, as indicated, carrying the receptacle b away from the lower end of the duct d , will also cause 100 the lower end of the duct to be closed by the surface of the disk b' and the upper surface of the material in the next receptacle b . The same sequence of events is then followed repeatedly, and it will be obvious that the successive operations will continually result in 105 taking material from the hopper a and forcing it into the duct d and also in forcibly discharging the material through the duct d no matter what the length of the latter and 110 in spite of any curves or branches that may be formed therein. The duct d may be, as mentioned above, designed in any manner so as to deposit the material at any desired point 115 without regard to direction or distance, and it may also deposit material in several places at the same time.

It will be evident that a device of the character set forth will be capable of many uses and that it can be substituted for chain-and-bucket or belt conveyers wherever they are commonly employed. Besides overcoming the objections mentioned in the first part of this specification it will be seen that it can be used for delivering coal to the hoppers of automatic stokers installed upon a coal-barge and could deliver the coal direct to the bunkers of steamships, that by the use of a flexible pipe supported by a hawser it could deliver coal from a steamship direct to the bunk- 125 130

ers of war and other vessels at sea, installed upon grain-carriers it can discharge the cargo without an elevator, and in factories it can be used to deliver any pulverized material 5 from place to place and at great distances. It will also be understood that the vertical form of the device shown in the drawings is not absolutely necessary, but that horizontal and inclined forms may be readily devised, all 10 coming within the scope of the present invention.

It will be readily seen that the device could be used for raising two or more kinds of material at the same time. This could be done 15 by installing another hopper over the idle receptacle at the lower right-hand side of Fig. 4 and another plunger and operating means under the next one above it, these two receptacles being idle when six receptacles are 20 used as shown. By having a large number of receptacles more than two kinds of material could be conveyed.

Having thus described my invention, I claim as new and desire to secure by Letters Patent—

25 1. A conveyer for solid material, comprising a movable receptacle, a plate thereabove having two openings, a hopper above one of said openings, a discharge-duct above the other opening, and means for forcing material 30 from the receptacle into said duct.

35 2. A conveyer for solid and granular material, comprising a series of rotary receptacles, a discharge-duct, and means for intermittently and successively forcing shapeless masses of material from the several receptacles into the duct.

40 3. A conveyer for solid material, comprising a rotary disk, a series of receptacles therein, open at the top and bottom, a plunger in each receptacle, and a vertical discharge-duct from the disk.

45 4. A conveyer for solid material, comprising a rotary disk having receptacles therein open at the top and bottom, a plate above the disk having two openings, a hopper in communication with one opening, a discharge-duct in communication with the other opening, plungers for the receptacles, means for intermittently rotating the disk, and means for 50 successively reciprocating the plunger.

55 5. A conveyer for solid granular material, comprising a hopper, a rotary disk having a series of open receptacles or perforations therein, a plunger in each receptacle, and a continuous discharge-duct located above the disk.

60 6. A conveyer for solid material, comprising a rotary disk having a receptacle therein, a plunger for the receptacle, a track for guiding the plunger, and means for reciprocating a portion of the track and the plunger.

7. A conveyer for solid material, comprising a rotary disk having receptacles therein, plungers in the receptacles, a track for guid-

ing the plungers, and a reciprocating device 65 located at a point in the track.

8. A conveyer for solid material, comprising a rotary disk, a series of receptacles therein, open at the top and bottom, and a plunger in each receptacle; each plunger having a 70 roller, a track for the rollers, and a reciprocating device located at a point in the track.

9. A conveyer for solid material, comprising a rotary disk, a series of receptacles therein, open at the top and bottom, and a plunger 75 in each receptacle; each plunger having a roller, a track for the rollers, and a reciprocating device located at a point in the track, said track having an inclined portion adjacent to the reciprocating device. 80

10. A conveying device, comprising a horizontal rotary table or disk having a concentric series of perforations therein, a vertical plunger in each perforation, means for intermittently rotating the table, and means for 85 raising one of the plungers in its perforation when the table is stationary.

11. A conveying device, comprising a horizontal rotary table or disk having a concentric series of perforations therein, a vertical plunger 90 in each perforation, means for intermittently rotating the table, means for raising one of the plungers in its perforation when the table is stationary, and means for permitting the plunger to be lowered when the table is given a rotary motion.

12. A conveying device, comprising a horizontal rotary table or disk having a concentric series of perforations therein, a vertical plunger 95 in each perforation, means for intermittently rotating the table, means for raising one of the plungers in its perforation when the table is stationary, and means for permitting the plunger to be lowered when the table is given a rotary motion; said last-named 105 means comprising a piston and means for intermittently operating the piston.

13. In a conveyer, the combination of a shaft having a pair of worms thereon, a cam connected to one of said worms, a piston operatively connected with said cam, a rotating device connected with the other worm, a table operatively connected with said rotating device and comprising a series of receptacles, a plunger in each receptacle adapted to be 110 brought into position immediately above said piston, and a track for supporting said piston. 115

14. In a conveying device, the combination of a shaft having a pair of worms thereon, a worm-wheel meshing with one of said worms, 120 a cog-wheel meshing with said worm-wheel, a disk, a shaft rigidly connecting said disk and cog-wheel, a series of receptacles in said disk, a plunger in each receptacle, a track for supporting said plungers, a piston located in said 125 track and adapted to reciprocate said piston, and connections from the other of said worms to said piston for reciprocating it.

15. In a conveying device, the combination of a rotary disk having a series of receptacles therein, a plunger in each receptacle, a track for supporting said plungers, means for rotating said disk and automatically stopping it at predetermined periods, and automatic means for raising one of said plungers when the disk is in a state of rest.

16. In a conveying device, the combination of a hopper, a disk having a series of receptacles therein, adapted to be moved immediately beneath said hopper, a discharge-duct located above said disk, means for rotating said disk intermittently, a plunger in each re-

ceptacle, automatic means for raising one of 15 said plungers when the disk is in a state of rest, means for permitting the plunger to drop when the disk is in a state of rotation, and means for guiding the plunger in its downward motion.

20 In testimony whereof I have signed my name to this specification in the presence of two subscribing witnesses.
